JOE M. PRESSLER, OF JACKSONVILLE, TEXAS.

PISTONLESS PUMP.

1,205,014.

Specification of Letters Patent. Patented Nov. 14, 1916.

Application filed March 22, 1916. Serial No. 85,830.

To all whom it may concern:

Be it known that I, JOE M. PRESSLER, a citizen of the United States, and a resident of Jacksonville, in the county of Cherokee and State of Texas, have invented a certain new and useful Improvement in Pistonless Pumps, of which the following is a specification.

My present invention relates generally to pumps and more particularly to water pumps though capable of use in connection with other fluids, my primary object being to provide an effective pistonless pump in order that it may be adaptable for use without undue wear in localities where sand predominates with the fluid to be pumped.

A further object of my invention is to provide a simple compact arrangement which will automatically operate in a continuous manner, thus obviating constant attendance and frequent repair.

The objects sought to be attained and the advantages derived from my present invention, have to do more particularly with the construction and operation of its several parts as hereinafter described with respect to the accompanying drawings, forming a part of this specification, and wherein—

Figure 1 is a vertical section through my improved pump, illustrating the parts in position at the beginning of inflow of water to the pump casing. Fig. 2 is a similar view illustrating the parts in position at the end of the inflow of water thereto. Figs. 3, 4, 5, and 6 are detail cross sections taken respectively on lines 3—3, 4—4, 5—5, and 6—6 of Fig. 1. Fig. 7 is a detail section through the three-way valve to be herein-after specifically referred to. Fig. 8 is a vertical section through the two lower floats. Fig. 9 is an enlarged vertical section through the upper portion of Fig. 1, showing the parts in position at the beginning of the outflow of fluid. Fig. 10 is a detail vertical section through the two upper floats, the lower one being latched. Fig. 11 is a similar view, the lower float being released. Fig. 12 is a detail section taken on line 12—12 of Fig. 11. Fig. 13 is a detail section taken substantially on line 13—13 of Fig. 12.

Referring now to these figures, my improved pump consists of an elongated cylindrical casing 25 to be lowered within a well casing 26 as particularly shown in Figs. 1 and 2, and almost or entirely submerged

therein below the normal level of the water therein, the upper end of the pump casing 25 being closed in air tight relation by means of a screw cap 27, and its lower end 60 being provided with a valved seat 28 upwardly presented and for the reception of a valve 29, the stem of which is freely adjustable in a guide 30 so as to permit the valve to raise under the external pressure 65 and permit the entrance of water as seen in Fig. 1, except when the pressure within casing 25 exceeds the external pressure, at which time the valve 29 will be closed.

Centrally depending within the cylindrical casing 25, is a cylindrical pump barrel 31 of substantially reduced diameter, as compared with that of the casing, so as to form an annular space between the same and the casing, the lower end of the barrel 75 31 terminating in a valved housing 32 above the lower end of the casing 25, and the upper end thereof being threaded within a central bearing of the casing cap 27 adjacent the lower end of an upwardly and outwardly leading water outlet pipe 33, by which the water pumped from the well may be carried away to a suitable point of disposition or use.

Leading downwardly and inwardly 85 through the cap 27 upon relatively opposite sides of the water outlet pipe 33, are a pair of air pipes 34 and 35, the former being the inlet air pipe and the latter the air exhaust pipe, the inner ends of these pipes, 90 within the casing 25, communicating respectively with valved air tubes 36 and 37 at the lower ends of which are valve seats for valves 38 and 39, the valve seats 40 and 41 being best seen in Fig. 9.

The valve seat 40 of the inlet air tube 36 surrounds an opening 42 through which the interior of the tube is in communication with the annular space around the barrel 31 when the valve 38 is open, the valve just mentioned, it being noted, seats downwardly upon its seat 40 and is provided with a depending stem 43 the lower end of which is connected to a piston 44 operating vertically within the piston cylinder 45, leading from relatively opposite ends of which cylinder are air tubes 46 and 47. Leading also from the upper end of the cylinder 45 adjacent air tube 46, is an exhaust air tube 48 having a check valve therein opening away from the cylinder 45, the opposite end of air tube 48 being connected to and communicating

with the exhaust air tube 37 before mentioned.

The air tubes 46 and 47 connected to opposite ends of the cylinder 45, lead to a three-way valve 50, leading also to which is an air tube 51 extending from the inlet air tube 36 and having a valve 52 therein opening away from the said air tube 36, the movements of the three-way valve 50 being controlled by an arm 52 depending therefrom and through the slot of a valve-actuating rod 53 extending vertically in the space between the barrel 31 and the casing 25 for nearly the full length of the barrel 31 and to which rod, adjacent the upper end thereof, is secured the valve 39 of the exhaust air tube 37. Thus, as will be seen by comparison of Figs. 7 and 9, when the valve-actuating rod 53 is in its uppermost position with the exhaust valve 39 seated against the exhaust valve seat 41 and the arm 52 of the three-way valve 50 in raised position, the valve 50 establishes communication between the air tubes 47 and 51 so as to admit the inlet air through said air tubes and into the lower end of the piston cylinder 45, raising the piston 44 and lifting the inlet air valve 38 upwardly off of the seat 40 so as to permit ingress of air from the air inlet 34 to the space between the barrel 31 and the casing 25 upon the surface of the water therein. In this way the necessary pressure is obtained upon the surface of the water within the casing 25 to force the column of water downwardly therein and upwardly within the barrel 31 through the lower upwardly opening valve 32^a of the latter located within its lower valve seat 32, the pressure at the same time closing the water intake valve 29 at the lower end of the casing 25 to prevent outflow of water from the casing except through the said valve 31. When the water level has been lowered and the supply of water practically exhausted, the valve actuating rod 53 is automatically lowered by means to be presently described, lowering the air exhaust valve 39 from its seat 41 and at the same time lowering the arm 52 of the three-way valve 50, so that the latter now in the position shown in dotted lines in Fig. 7, communicates between and connects the air tubes 46 and 47, the pressure in the space around the barrel 31 exhausting out through the exhaust air tube 37. Thus with air tubes 46 and 47 communicating, pressure is equalized within the piston cylinder 45 upon opposite sides of the piston 44, and excess pressure is permitted to escape through the valved tube 48 to the exhaust tube 37, the inlet air in the air tube 36 acting then upon the upper face of the inlet valve 38, of less diameter than that of piston 44, to lower valve 38 upon its seat 40 and thus cut off the intake of air to the casing. Upon the lowering of pressure within the casing, the water intake valve 29 then opens under the exter-

nal pressure, and water from the well finds its way freely within the casing 25, the lower valve 32^a of the barrel 31 being then held downwardly in closed position against its seat 32^a by means of the pressure of the water column within the barrel 31.

The upper and lower portions of the valve actuating rod 53 pass respectively through bearings 55 and 56 and adjacent these bearings, the said valve rod is respectively provided with stops 57 and 58. Freely slidable on the valve rod 53 in the space between the barrel 31 and the casing 25, are pairs of floats, of which the floats of the upper pair are indicated at 59 and 60, and the floats of the lower pair are indicated at 61 and 62, the upper floats acting at the proper time against the upper stop 57 of the valve rod, and the lower floats operating also at the proper time against the lower stop 58 of the valve rod. The lower floats 61 and 62 operate also upon guides 63 and 64, the former of which is common also to the upper floats 59 and 60, and the latter of which is of a length approximately that of the combined movement of the floats 61 and 62, its ends being secured in brackets 65 so as to prevent longitudinal movement thereof.

The guide 64 has an intermediate longitudinal slot, as seen in Fig. 8, and within this slot is intermediately pivoted at 66, a latch member 67, the lower end of which is laterally extended at 68 and works within an inclined opening within the lower float 62 of the pair, the upper end of the latch member 67 being thus shiftable laterally into and out of the slot of the guide 64 wherby, when shifted outwardly thereof, as seen in Fig. 8, it will engage a latch piece 70 at the lower surface of the upper float 61 and thus latch the upper float 61 in raised position until the lower float 62 has lowered to a point adjacent the stop 58 of the valve actuating rod 53, at which point the inclined opening of the lower floats will shift the latch 67 so as to free its upper end from the upper float and permit the latter to drop against the lower float, the combined action of these two serving to lower the valve actuating rod 53 by their engagement with the stop 58. This action takes place when the water lowers in the casing 25, from the action of the air pressure upon the surface thereof in driving the water upwardly and outwardly through the barrel 31 and serves to reverse the air valve so as to cut off the air inlet and permit the air pressure to exhaust, as before described. The floats 59 and 60 of the upper pair are also mounted upon guides, one of which is the beforementioned guide 63 as shown in Fig. 8, and the other of which is a longitudinally immovable guide 71 having an intermediate longitudinal slot in which is intermediately pivoted at 72, a latch member 73 similar to,

although in reversed position with respect to, the latch member 67 before mentioned, the upper end of latch member 73 being laterally extended as seen at 74 in Fig. 10 and working within an inclined slot 75 in the upper float 59, and the lower end thereof being laterally shiftable into and out of the slot of the guide 71 and into and out of engagement with a spring controlled latch piece 76 in the upper surface of the lower float 60 of the pair. Thus, when the head of water within the casing 25 rises, the upper floats will rise independently of the lower float 60 by virtue of the fact that the latter is latched in its lowermost position. This independent movement of the upper float 59 will continue until the latter is contiguous to the upper stop 57 of the valve actuating rod 53, at which time the action of its inclined slot upon the upper laterally extended end 74 of the latch 73 will shift the latch laterally and disengage its lower end from the latch piece 76, thus freeing the float 60 which will immediately rise and strike the float 59, the combined action of the two floats upon the stop 57 serving then to raise the valve actuating rod 53, closing the exhaust valve 30, and raising the arm 52 of the three-way valve 50 so as to shift the air controlling parts back to the position shown in Fig. 9, and again provide for the inlet of air to act upon the normal level of water within the casing 25 which air serves to hold the exhaust valve 39 closed, and consequently maintain the rod 53 in uppermost position until the combined action of floats 61 and 62 lowers the rod and opens the valve 39 in a manner previously described.

Thus, from the foregoing it will be seen that I provide a compact apparatus for the purpose described, the several parts of which are inclosed within the upper end of the casing 25, and may be entirely removed from the casing with the removal of the barrel 31 to permit of substitution and repair.

I claim:

1. A pump of the type described comprising a casing having a water intake valve, a pump barrel within the casing having valved communication therewith, air inlet and exhaust pipes, valves controlling communication between said inlet and exhaust pipes and said casing, air actuated means controlling the inlet valve and including a piston connected to the said valve, a cylinder in which said piston is movable, a valved air pipe connecting one end of said cylinder with said exhaust pipe, a second valved air pipe leading from the said inlet pipe, a pair of cylinder pipes leading from adjacent relatively opposite ends of said piston cylinder, a three-way valve controlling communication between said cylinder pipes and the said second valved air pipe, a valve rod having connections for controlling said three-way valve and also controlling said exhaust pipe valve, and means for automatically actuating said valve rod including floats having limited movement thereon and with respect thereto, and arranged within the casing for actuation by the rise and fall of water therein.

the said second valved air pipe, a valve rod having connections for controlling said three-way valve and also connected to and controlling said exhaust pipe valve, and means for automatically actuating said valve rod including floats having limited movement thereon and with respect thereto, and arranged within the casing for actuation by the rise and fall of water therein.

2. A pump of the type described comprising a casing having a fluid intake valve at its lower end, a pump barrel within the casing and having valved communication at its lower end with the casing, air inlet and exhaust pipes, valves controlling communication between said inlet and exhaust pipes and said casing, air actuated means for controlling the said inlet valve, a valve actuating rod controlling the said air actuated means and also connected to and controlling the said exhaust pipe valve, and means for automatically actuating said valve rod including stops carried thereby adjacent its upper and lower ends, floats mounted in pairs and movable upon the valve actuating rod adjacent the upper and lower ends thereof and adjacent said stops, each of said pairs of floats having a guide, a latch carried by the guide and engaging one of the floats of the pair to permit of relative movement of the other floats, the said other floats being provided with means for releasing the latch, all substantially as described.

3. A pump of the type described comprising a casing having a fluid intake valve, a pump barrel within the casing having valved communication therewith, air inlet and exhaust pipes, valves controlling communication between the inlet and exhaust pipes and said casing, a piston controlling the said inlet valve, a cylinder in which said piston is movable, a valved air pipe connecting one end of said cylinder with said exhaust pipe, a second valved air pipe leading from the said inlet pipe, a pair of cylinder pipes leading from adjacent relatively opposite ends of said piston cylinder, a three-way valve controlling communication between said cylinder pipes and the said second valved air pipe, a valve rod having connections for controlling said three-way valve and also controlling said exhaust pipe valve, and means for automatically actuating said valve rod including floats having limited movement thereon and with respect thereto, and arranged within the casing for actuation by the rise and fall of water therein.

4. A pump of the type described comprising a casing having a fluid intake valve, a pump barrel within the casing having valved communication therewith, air inlet and exhaust pipes, valves controlling communication between the inlet and exhaust pipes and said casing, a piston controlling

the said inlet valve, a cylinder in which said piston is movable, a valved air pipe connecting one end of said cylinder with said exhaust pipe, a second valved air pipe leading from the said inlet pipe, a pair of cylinder pipes leading from adjacent relatively opposite ends of said piston cylinder, a three-way valve controlling communication between said cylinder pipes and the said 10 second valved air pipe, a valve rod having connections for controlling said three-way valve and also controlling said exhaust pipe valve, and means for automatically actuating said valve rod including floats having 15 limited movement thereon and with respect thereto, and arranged within the casing for actuation by the rise and fall of water therein, said floats being arranged in pairs adjacent the upper and lower ends of the 20 valve actuating rod and of which each pair has a latch engaging one of the floats of the pair and the other float of the other pair is provided with means for releasing said latch.

25 5. A pump of the type described comprising a casing having a water intake valve, a pump barrel within the casing having valved communication therewith, air inlet and exhaust pipes, valves controlling communication between said inlet and exhaust 30 pipes and said casing, air operated means for controlling the said inlet valve, a valve actuating rod carrying the said exhaust pipe valve and having connections for controlling the said air operated means, and means for automatically actuating said valve rod arranged within the casing for actuation by the rise and fall of water therein.

35 40 6. A pump of the type described com-

prising a casing having a fluid intake valve, a pump barrel within the casing having valved communication therewith, air inlet and exhaust pipes, valves controlling communication between said inlet and exhaust 45 pipes and said casing, a piston controlling the said inlet valve, a cylinder in which said piston is movable having a valved connection with the exhaust pipe and having air pipes leading from its opposite ends, a 50 valved air pipe leading from the inlet pipe, a three-way valve controlling communication between said cylinder pipe and the said valved inlet air pipe, a valve rod having connections for controlling said three-way valve and upon which the said exhaust pipe valve is secured, and means for automatically actuating said valve rod arranged within the casing for actuation by the rise and fall of water therein.

55 7. A pump of the type described comprising a casing having a fluid intake valve, a pump barrel within the casing having valved communication therewith, said casing having an air inlet and an air exhaust, 60 valves controlling communication between said inlet and said exhaust and the said casing, air actuated means having valved communication with both the air inlet and the air exhaust, for controlling the valve of the air inlet, and mechanical means for controlling the said air actuated means and the valve of the exhaust, said last named means being in the form of a vertically movable rod arranged within the casing 70 and acted upon by the rise and fall of fluid therein, said rod supporting the valve of the exhaust and having connection with the valve of the said air actuated means.

JOE M. PRESSLER.
